UNITED STATES PATENT OFFICE.

JAMES COSGROVE, OF FLATBUSH, NEW YORK.

PAPER BARREL.

SPECIFICATION forming part of Letters Patent No. 309,768, dated December 23, 1884.

Application filed June 9, 1884. (No model.)

To all whom it may concern:

Be it known that I, JAMES COSGROVE, of Flatbush, in the county of Kings and State of New York, have invented a new and useful Improvement in Paper Barrels, of which the following is a full, clear, and exact description.

Reference is to be had to the accompanying drawings, forming a part of this specification, in which similar letters of reference indicate corresponding parts in all the figures.

Figure 1 is a plan view of the shell of the barrel before being put into shape. Fig. 2 is an edge view of the same, partly in section, through the line $\alpha\alpha$, Fig. 1. Fig. 3 is a side elevation of the completed barrel, part broken away. Fig. 4 is an end elevation of the same, part being broken away.

The object of this invention is to provide paper barrels for holding light and dry substances for storage and transportation, which shall be strong, light, and durable, and comparatively inexpensive in manufacture.

The invention consists in a paper barrel formed of a shell made in one piece, with flaring slits in its side edges to give a taper to the end parts of the barrel, shoulders in its side edges to form seats for the heads, and flanges at its end edges to prevent the said edges from slipping past each other, the said shell and heads being fastened together by hoops, as will be hereinafter fully described, and specifically set forth in the claims.

A represents the shell of the barrel, which is made of paper of the requisite thickness, and in sheets of such a length that each sheet will form a barrel. The sheet A is made with flaring slits B in its side edges to give the desired taper to the end parts of the barrel, and with a shoulder, C, along its side edges to form seats for the heads D. The end edges of the sheet are thickened to form ribs or flanges E, as shown in Figs. 1, 2, and 4, to

prevent the said edges from slipping past each other when the said sheet is bent together into 45 barrel form.

The sheet A is designed to be made at the paper-mill, with the slits B, the shoulders C, and the flanges E, and with the parts between the said slits B slightly concaved, so that the 50 end parts of the barrel will have a circular form to cause the hoops F to fit snugly upon them.

It should be observed that the slits B will need to be trimmed after the sheets A come 55 from the paper-mill to cause the edges of the said slits to fit each other closely.

The hoops F are applied in the ordinary manner, and may be made of paper covered with cloth, of paper covered with wood, or 60 wholly of wood, or of other suitable material that has the necessary lightness and strength.

Barrels thus made will be strong, light, durable, inexpensive, and very serviceable for holding light and dry substances for storage 65 and transportation.

Having thus described my invention, I as new and desire to secure by Letters Patent—

1. A paper barrel made substantially as herein shown and described, and consisting 70 of the shell A, made in one piece, with flaring slits B and shoulders C in its side edges, and flanges E along its end edges, the heads D, and the hoops F, as set forth.

2. In a paper barrel, the shell A, made substantially as herein shown and described, with flaring slits B in its side edges to give a taper to the end parts of the barrel, shoulders C in its side edges to form seats for the heads D, and flanges E at its end edges to prevent the 80 said ends from slipping past each other, as set forth.

JAMES COSGROVE.
